(57) **CLAIM**

The ornamental design for a connector nut, as shown and described.

DESCRIPTION

FIG. 1 is a perspective view of a connector nut in accordance with the present invention;

FIG. 2 is a front view of the connector nut of FIG. 1;

FIG. 3 is a back view of the connector nut of FIG. 1;

FIG. 4 is a left side view of the connector nut of FIG. 1;

FIG. 5 is a right side view of the connector nut of FIG. 1;

FIG. 6 is a top view of the connector nut of FIG. 1; and,

FIG. 7 is a bottom view of the connector nut of FIG. 1.

The broken lines in the drawings illustrate portions of the connector nut and form no part of the claimed design.

1 Claim, 5 Drawing Sheets
